UNITED STATES PATENT OFFICE.

HENRY C. MILLER, OF WATERFORD, NEW YORK.

NEEDLE AND SHUTTLE THREAD CUTTING DEVICE FOR SEWING-MACHINES.

SPECIFICATION forming part of Letters Patent No. 793,007, dated June 20, 1905.

Application filed August 1, 1903. Serial No. 167,912.

To all whom it may concern:

Be it known that I, HENRY C. MILLER, a citizen of the United States, and a resident of Waterford, in the county of Saratoga and State 5 of New York, have invented certain new and useful Improvements in Needle and Shuttle Thread Cutting Devices for Sewing-Machines, of which the following is a specification.

The object of the invention is to provide a 10 thread-cutting attachment for a sewing-machine which will enable an operator to quickly and conveniently move the needle and shuttle thread along a guide, the needle-thread engaging a holder and held thereby while said 15 thread and the shuttle-thread are simultaneously severed.

After a piece of fabric has been stitched and the needle and shuttle threads have been severed operators have experienced considerable 20 difficulty in preventing the needle-thread from slipping from the eye of the needle. By my invention I have overcome this difficulty by arranging means by which two threads when moved together will be automatically separated 25 and simultaneously severed.

Other objects and advantages will be hereinafter described and be particularly pointed out in the claims.

In the drawings, Figure 1 is a plan view of 30 my invention applied to a portion of a sewing-machine. Fig. 2 is a similar view on an enlarged scale. Fig. 3 is a front elevation, the presser-foot to which the invention is applied being down in operative position. Fig. 35 4 is a side elevation, the presser-foot being raised for the withdrawal of a stitched piece of fabric. Fig. 5 is a view similar to Fig. 4 with the presser-foot down and ready for stitching. Fig. 6 is a detail enlarged side 40 view of the invention.

Similar letters of reference indicate like parts in the several views.

A indicates a sewing-machine table; B, a needle-bar; b, the needle; b', the thread carried by the needle; b'', the shuttle, and b''' the shuttle-thread.

C is a cloth-plate supported from table A.

D is a presser-foot secured to the support D', pivoted on a bracket E by a pivot d'.

50 F is a lever which is connected with sup-

port D', to which presser-foot D is connected, and serves when pressed down as a convenient means for raising the presser-foot from the fabric on the cloth-plate C, and F' is a spring operating to hold the presser-foot down. 55

The parts thus far described are old in the art and form no part of this invention, and further description is deemed unnecessary.

The presser-foot D comprises the two longitudinal bars d' d'', which depend from the 60 plate G and are adapted to be raised and lowered by operating the lever F. The lower edges of the bars d' d'' of the presser-foot are provided with teeth d' d'', as shown in Fig. 3, and the plate G is formed with an opening 65 G', Figs. 1 and 2, for viewing the fabric when it is being placed between the cloth-plate and the presser-foot. The plate G is also provided with an extension g, which is extended forward from the presser-foot D and is adapted to receive on its upper side the thread-cutting knife H and on its lower side the needle-thread holder I.

As stated, the knife H is mounted on the upper side of the front extension g of plate G 75 and has its cutting edge h made beveled and on a line which is inclined or at an angle in relation to the edge g' of the extension g, as shown in Fig. 2, so that the cutting edge of the knife may run forward and off from the 80 top surface of plate G. In the forward edge g' of the plate G is a notch h', forming a temporary thread-retainer for the needles and shuttle-threads b' and b'' preparatory to being severed. The notch prevents the operator 85 drawing the threads off the edge g' when taking the fabric from under the presser-foot, which would necessitate considerable loss of time, as will be readily understood. The knife H is adjustable in relation to the cloth-plate and is preferably made so by slot h'' and the binding-screw h'', by means of which the 90 knife may be removed for sharpening and be replaced and adjusted as may be required.

To the under side of the extension g of the 95 plate G is secured by a rivet r', passing through an extension r'', a thread-retainer I, which is made to yield to gently press on the needle-thread when drawn away from notch h' toward the point h', where the edge of the knife in- 100

tersects the edge of the plate G, as will be hereinafter explained. The yielding thread-retainer is constructed of thin steel and is secured in position back of edge h of the knife 5 H, with its front edge i in alinement with the edge g', as shown in Figs. 2 and 6. The free end of this thread-retainer is provided with a downwardly-extending lip i', adapted to guide the needle-thread between the upper side of 10 the retainer I and the lower side of plate extension g, the thread being held and prevented from being drawn out and becoming loose. When the piece of fabric (not shown) has been stitched and ready for removal from the 15 sewing-machine, the operator will draw down the lever F, which elevates the presser-foot, to free the fabric and allow of its being removed. The operator will in removing the stitched fabric carry the needle-thread b' and the 20 shuttle-thread b² into the temporary thread-retainer notch h'. The stitched piece having been removed, the operator will quickly move it in the opposite direction, which will carry the threads b' b² toward the knife-edge h, and 25 by reason of the positions of the parts the needle-threads b' will be caught by the holder I, while the shuttle-thread will pass it, and by a continued movement of the two threads they both engage the edge of the knife and 30 are simultaneously severed thereby. The threads having been severed, the free end of the shuttle-thread b² drops onto the cloth-plate, while the severed end of the needle-thread b' is held by the holder with relation 35 to the eye of the needle, which enables me to tightly close on the shuttle-thread at the first stitch when stitching the next piece of fabric. It will therefore be understood that by the several operations of the respective parts the 40 shuttle-thread may be severed at a point to leave a sufficient length of thread to fall to be clamped between the cloth-plate and the fabric to be stitched, so that it will at first commencement of stitching be in proper place. 45 Having described my invention, what I claim, and desire to secure by Letters Patent, is—

1. The combination with a presser-foot of a sewing-machine and a plate which is stationary in relation to said presser-foot, one edge of said plate being formed with a notch to provide a temporary thread-retainer, a thread-holder spaced from the temporary thread-retainer, a thread-cutting knife secured to the 50 stationary plate with its cutting edge at an angle to the line of the edge of said plate having the notch, the edge of the plate and knife forming a guide between the temporary thread-retainer and the point of intersection 55 of the knife and the plate.

2. The combination with a presser-foot of a sewing-machine, a plate, a thread-cutting knife mounted on the plate and projecting outwardly herefrom, with its cutting edge toward the 60 aid presser-foot and at an angle with the line

of front edge of said plate, a temporary thread-retaining notch formed in the plate for assembling the needle-thread and lower thread, a thread-retainer fixed to the said plate and adjacent the cutting edge of the knife adapted 70 to receive the needle-thread and hold same when moved along the edge of the plate from the temporary retainer, the needle-thread and lower thread being simultaneously severed by the knife. 75

3. A combined thread cutter and holder comprising a plate, a thread-holder on the plate, a knife on the opposite side the plate and spaced by the latter from the holder, the edge of the plate serving as a guide for two 80 threads, one of which is caught by the holder and both threads being severed by the knife.

4. The combination with a presser-foot of a sewing-machine, of a thread-cutting blade which is held stationary in relation to the 85 presser-foot, the blade being relatively forward of the presser-foot with its cutting edge toward the same, of an elastic needle-thread retainer secured in place below the plane of and spaced from the cutting edge of the blade, 90 the blade and elastic retainer being so positioned with relation to each other that a needle-thread will be held by the retainer and a lower thread pass free of the same, the two threads being simultaneously severed. 95

5. The combination with a plate which is connected with a presser-foot of a sewing-machine, of a thread-cutting blade which is mounted on the said plate, and is adapted to be adjusted longitudinally on the same and 100 has its cutting edge at an angle in relation to the line of the forward edge of said plate, a thread-assembling notch formed in the edge of the plate in front and to one side the needle, a needle-thread-retaining device opposite 105 the said cutting-blade and beneath the said plate, and means for raising and depressing said plate.

6. The combination with a cloth-plate, a presser-foot, mechanism adapted to elevate 110 and depress said presser-foot, a plate which is stationary in relation to said presser-foot, an extension on the plate, a thread-retainer, a thread-severing blade connected with the upper side of an extension of the plate and arranged to have its cutting edge at an angle to the front edge of the extension, a thread-assembling notch formed in the plate, the edge of the plate serving as a guide for guiding the assembled needle and shuttle threads to 115 the point of intersection of the cutting edge of the blade with the edge of said plate, one of said threads engaging the thread-retainer.

7. A sewing-machine attachment comprising a thread-holding device, a knife spaced 120 from the thread-holding device, and a guide between the thread-holding device and the knife.

8. In combination, a stitching mechanism comprising a lower-thread carrier, needle and 130

presser-foot, a knife, a thread-holder spaced from the knife, and a guide between the knife and thread-holder, the knife and thread-holder being so located relative to the sewing-
5 machine that when the presser-foot is elevated, a selected thread can be held by the thread-holder, and the needle and lower threads will be simultaneously severed, both threads being directed by the guide.

10. 9. A thread holding and cutting device comprising a plate formed on one edge with a notch to provide a temporary thread-holder, a thread-holding device fastened under the plate, a knife on top of the plate and spaced
15 from the thread-holder, the temporary thread-holder and thread-holding device being spaced from each other.

10. In combination, a sewing-machine comprising stitching mechanism, a movable press-
20 er-foot having a plate, and a throat-plate formed with an opening below the presser-
foot, a knife, a thread-holding device under the plate and adjacent the knife, the knife

and thread-holder being positioned with relation to the plate of the presser-foot and throat-
25 plate, so that when the presser-foot and plate are elevated the needle-thread when drawn along the edge of the plate will be in line to engage the thread-holder and the lower thread will pass the holder, both threads engaging
30 the knife and being severed thereby.

11. In combination, a sewing-machine provided with a presser-foot, a throat-plate having an opening, a thread-holding device, a guide, and a knife positioned relative to the
35 thread-holder so that when the presser-foot is raised the position of the thread-holder will be such that the needle-thread may be guided to and held by said thread-holding device, said needle-thread and the lower thread upon fur-
40 ther movement on the guide will engage the knife and be severed thereby.

HENRY C. MILLER.
